UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL COMPOSING AND DISTRIBUTING MACHINE.

Application filed April 12, 1924. Serial No. 706,004.

To all whom it may concern:

Be it known that I, DAVID S. KENNEDY, a citizen of the United States, residing at Brooklyn, in the county of Kings and State of New York, have invented certain new and useful Improvements in Typographical Composing and Distributing Machines, of which the following is a specification.

This invention relates to typographical machines, such as linotype machines of the general organization represented in the Mergenthaler Patent No. 436,532, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter elevated and returned through distributing mechanism to the magazine from which they started. More particularly, it relates to that class of machines equipped with a series of magazines movable to bring different selected pluralities thereof into operative relation to the distributing mechanism and capable of a further movement to locate any magazine of the selected plurality in operative relation to the assembling mechanism. Such a machine is fully disclosed in and covered by the Röger Patent No. 1,161,161, to which reference may be had for any further details or information.

The present invention is directed to certain improvements in machines of the class stated and contemplates a construction which may be readily adapted to commercial linotype machines and with the minimum of change. In the preferred embodiment illustrated, the magazines are carried by a supporting frame, which is movable in a rectilinear path to bring a selected plurality into operative relation to a corresponding plurality of main distributors, and they (the magazines) are pivotally mounted upon said supporting frame so that one or another of the plurality thus selected may be swung into or out of operative relation to a single assembler entrance. These and other improvements will be more fully pointed out in the detailed description to follow.

In the accompanying drawings, the im-

provements have been shown merely in preferred form and by way of example, and, obviously, many changes and variations may be made therein and in their mode of application, which will still be comprised within the spirit of the invention. Generally speaking, the invention is not limited to any specific form or embodiment, except in so far as such limitations are specified in the claims.

Referring to the drawings:

Fig. 1 is a side elevation, partly in section, of a linotype machine equipped with the present improvements and showing the upper magazine in use;

Fig. 2 is a similar view but showing the middle magazine in use;

Fig. 3 is a transverse section taken on line 3—3 of Fig. 2;

Fig. 4 is a view similar to Fig. 2 but showing the magazine supporting frame in its upper position; and

Fig. 5 is an enlarged detail section taken on the line 5—5 of Fig. 1.

In the present instance, the improvements are shown as applied to a machine equipped with three magazines A, a single assembler entrance B, and two magazine entrances F, the latter leading from two main character distributors E, which receive the matrices X from a font separator D in the usual well known manner.

Each of the magazines A is provided with matrix releasing escapements C, which, when the magazine is in use, are actuated through the medium of pivoted levers C¹ by reeds C², controlled in the usual way from a keyboard (not shown).

The several magazines A are mounted upon separate base frames A¹ carried by a supporting frame A³, which latter is arranged to be moved upwardly and downwardly in a rectilinear path to bring any selected pair of adjoining magazines in operative relation to the two magazine entrances F. As shown in Fig. 1, the frame A³ is attached to a sliding plunger L adapted to be raised and lowered within a fixed sleeve O by screw thread mechanism, actuated through a connecting shaft L¹ by a hand crank L², conveniently located for manipulation by the operator. In order to guide the magazine supporting frame in its rectilinear movements, it is provided at its upper end with perpendicular corner

members A^4 arranged in sliding engagement with supplementary brackets O^2 , secured to the inner faces of the main distributor bracket O^1 . Since the magazines are selected in pairs, it is only necessary to locate the magazine supporting frame in two different positions, one as indicated in Figs. 1 and 2 for the upper pair, and the other as indicated in Fig. 4 for the lower pair.

Any suitable means may be employed for the purpose, but as herein shown, such means comprise a pair of fore and aft bars J , slideable longitudinally on opposite sides of the machine and held normally in their active positions by springs J^1 . These bars are each provided with upper and lower locating blocks J^2 , J^3 , adapted to engage finished lugs projecting from the opposite sides of the frame A^3 . A hand lever J^4 , fastened to one end of a transverse rock shaft J^4 having arms J^5 engaged with pins on the bars J , serves to withdraw the blocks out of engagement with the frame A^3 when it is to be shifted from one position to the other.

The magazine base frames A^1 are mounted upon the shiftable supporting frame A^3 in such manner that the magazines may be moved as a unit relatively thereto so as to locate either magazine of the selected pair in operative relation to the assembler entrance B and the escapement actuating levers C^1 without disturbing the connection with the magazine entrances F . To this end, the base frames are provided at their upper ends and at opposite sides with laterally projecting pivot pins A^5 seated in notches A^6 formed in the rear edges of the corner members A^4 , it being noted that sufficient space is allowed between the lowermost base frame and the supporting frame A^3 to permit the required movement of the magazine unit. As shown, the pivotal axis of each base frame is located in the central longitudinal plane and at the extreme upper end of the magazine mounted thereon, and hence when the base frames are swung about their respective axes, the pivotal movement of the selected magazines at their entrance ends is so slight as not to disturb the proper relation to the magazine entrances. At their lower ends, the base frames A^1 are provided with depending gage blocks A^2 , those of each frame resting loosely upon aligning surfaces formed on the next underlying frame except in the case of the lowermost base frame which has its gage blocks arranged to bank upon aligning lugs A^7 on the supporting frame A^3 when the magazine unit occupies its downwardly swung position, as in Fig. 4. It will now be clear that, when a pair of magazines is brought into operative relation to the two magazine entrances by the shifting of the supporting frame A^3 , either magazine of that pair may

be located in operative relation to the assembler entrance B and the escapement actuating levers C^1 by swinging the magazine unit upwardly or downwardly relatively to the supporting frame. During the shifting of the supporting frame, the magazine unit occupies its downwardly swung position (resting upon the aligning lugs A^7), so that the upper magazine of the selected pair is located in registration with the assembler entrance directly by the shifting of the supporting frame (see Figs. 1 and 4), but when it is desired to locate the lower magazine of the selected pair in such delivery position, the magazine unit is swung upwardly about the pivotal axes of the base frames, as in Fig. 2.

Means are therefore provided for effecting the required swinging movements of the magazine unit in either shifted position of the supporting frame. In the embodiment illustrated, such means consist essentially of a toggle system, which, when straightened out or extended, raises the magazine unit to place the lower magazine of the selected pair in operative relation to the assembler entrance, and which, when collapsed, allows the unit to swing downwardly until it comes to rest upon the supporting frame with the upper magazine of the selected pair in operative position. The toggle system comprises two pairs of links H , H^1 , intermediate connected by a transverse rod H^2 , to which the lower members H^1 are made fast and on which the upper members H are loosely mounted (Fig. 3). The members H^1 are pivotally mounted on pins fastened in brackets O^5 , which constitute part of the machine frame, while the members H , at their upper ends, are formed with open bearings or forks h , for engagement with one or the other pair of pins A^{10} which project inwardly from two fingers A^9 , depending from the lowermost base frame A^1 at opposite sides and near the lower end thereof. The pins A^{10} are disposed at different levels, that is, one pair above the other, so that, when the supporting frame A^3 is in its lower position (Figs. 1 and 2), the upper pair will be located in position to be engaged by the forked members H and, when the said frame is in its upper position (Fig. 4), the lower pair will be similarly located. The toggle system is actuated by a hand lever H^5 , fastened to one end of a transverse rock shaft H^4 provided near the center with a forked arm H^6 engaged with the connecting rod H^2 , Fig. 3.

With particular reference to Figs. 1 and 4, it will be noted that the parts are so arranged that the engagement between the magazine unit and the toggle system is broken when the latter is in its collapsed condition. In other words, a slight lost motion or overthrow of the hand lever H^5

is permitted after the lower base frame contacts with the supporting frame, a stop H^7 (see dotted lines, Fig. 1) being employed to arrest the parts in their proper condition. In order to prevent the total collapse of the upper members H of the toggles after their disengagement from the pins A^{10} and to sustain them in proper position for reengagement therewith, there are provided 10 stop lugs O^6 extending inwardly from the brackets O^5 and cooperating with flanges on the sides of said members (Fig. 3). Accordingly, by this arrangement, the magazine supporting frame A^3 may be moved upwardly or downwardly in the machine without interference with the toggle system, while the latter is maintained in condition to cooperate with the magazine unit in either shifted position of said frame.

20 Counterbalancing means are also employed to facilitate the swinging of the magazines, such means (Figs. 1 and 2) comprising a lever G , pivoted to the supporting frame A^3 and loosely connected at its forward end to the lowermost base frame A^1 . A strong spiral spring G^1 , connected to the opposite end of said lever, is enclosed within and fastened to the lower end of a tube G^2 , secured to and depending from the frame 25 A^3 . The spring thus materially assists the operator in raising and lowering the magazine unit.

In order to insure the required registration of both magazines of a selected pair with 30 the assembler entrance B without danger of interference, it is proposed to shift the pivots of those magazines relatively to each other so as to locate them in different planes disposed at right angles to the magazines. Hence, the pivot pins A^5 are made long enough to project through the notches A^6 and far enough beyond to engage cam plates O^3 , fastened to the rear edges of the brackets O^2 (see 40 Fig. 5). These cam plates are of a predetermined thickness and are located at such height as to engage the pivot pins of the lower magazine of either selected pair but to stand clear of the pivot pins of the 45 upper magazine of that pair. Due to the rearward displacement of its pivotal axis, the lower magazine may be swung freely into or out of action, as desired. It may be noted that such displacement of the pivot pins will in no way interfere with the fanning apart of the magazines in the usual 50 way for removal and replacement. At such times, the pivot pins will function as heretofore.

55 It may be observed that, in the use of the two different pairs of magazines, the middle magazine will at one time be connected with the front distributor and at another time with the rear distributor. To 60 enable the matrices contained in said maga-

zine to select one or the other of these two distributors, the font separator D is adjusted whenever a change is made from one pair of magazines to the other. This may be done manually or automatically, as 70 preferred. A suitable automatic arrangement is disclosed in the Billington Patent No. 1,427,511, or the Drake Patent No. 1,427,517.

75 As previously stated, the improvements have been shown only in preferred form and by way of example and as applied to a particular class of machines. Many modifications and alterations therein and in their mode of application will readily suggest 80 themselves to those skilled in the art without departure from the scope of the invention.

Having thus described my invention, its 85 construction and mode of operation, what I claim and desire to secure by Letters Patent of the United States, is as follows:

1. In a typographical machine equipped 90 with assembling and distributing mechanisms, the combination of a magazine unit comprising a series of magazines, a supporting frame for said magazine unit, means for shifting the supporting frame to locate a selected plurality of magazines in operative relation to the distributing mechanism, and means for moving the magazine unit relatively to the supporting frame to bring any magazine of the selected plurality into operative relation to the assembling mechanism. 100

2. In a typographical machine equipped 105 with assembling and distributing mechanisms, the combination of a magazine supporting frame, a series of magazines pivotally mounted thereon, means for shifting the supporting frame in a rectilinear path to bring a selected plurality of magazines into cooperation with the distributing mechanism, and means for swinging the magazines relatively to the supporting frame to bring any one of the selected plurality into operative relation to the assembling mechanism. 110

3. In a typographical machine equipped 115 with assembling and distributing mechanisms, the combination of a plurality of magazines, a supporting frame therefor shiftable to bring a selected plurality of magazines into operative relation to the distributing mechanism, magazine base frames pivoted at their upper ends to the supporting frame, means for effecting the shifting of the magazine supporting frame, and additional means for swinging the base frames about their respective pivots to locate any magazine of the selected plurality in operative relation to the assembling mechanism. 120

4. In a typographical machine, the combination with a series of magazines, a plu- 130

rality of distributors, and an assembler entrance, of a supporting frame for the magazines shiftable to bring a selected plurality thereof into operative relation to the distributors, and means for moving the magazines relatively to said supporting frame to locate one or another of the selected plurality in operative relation to the assembler entrance.

10 5. In a typographical machine, the combination with a plurality of distributors, magazine entrances leading therefrom, and an assembler entrance, of a series of magazines arranged between the assembler entrance and the magazine entrances, a supporting frame whereon the magazines are pivotally mounted at their upper ends, means for shifting the supporting frame to bring a selected plurality of magazines in operative relation to the magazine entrances, and means for swinging the magazines about their respective pivots to locate any one of the selected plurality in operative relation to the assembler entrance without disturbing their operative relation to the magazine entrances.

20 6. In a typographical machine equipped with assembling and distributing mechanisms, the combination of a plurality of parallel magazines, a magazine supporting frame shiftable in a rectilinear path to bring a selected plurality of magazines into cooperation with the distributing mechanism, and means cooperating with the magazines in different shifted positions of the supporting frame to locate any one of the selected plurality in operative relation to the assembling mechanism.

40 7. In a typographical machine equipped with assembling and distributing mechanisms, the combination of a plurality of magazines, a supporting frame therefor provided with perpendicular corner members and shiftable to bring a selected plurality of magazines into operative relation to the distributing mechanism, magazine base frames pivoted at their upper ends to said corner members, means for effecting the shifting of the magazine supporting frame, and additional means, comprising manually controlled toggle devices arranged to cooperate with extensions on the lowermost base frame, for swinging the base frames about their respective pivots to locate any magazine of the selected plurality in operative relation to the assembling mechanism.

60 8. In a typographical machine equipped with assembling and distributing mechanisms, the combination of a plurality of magazines, a supporting frame shiftable to bring a selected plurality of magazines into operative relation to the distributing mechanism, magazine base frames pivoted at their upper ends to the supporting frame, means

for effecting the shifting of the magazine supporting frame, and additional means arranged to engage the lowermost base frame in any shifted position of the supporting frame for swinging the base frames as a 70 whole about their respective pivots to locate any magazine of the selected plurality in operative relation to the assembling mechanism.

9. In a typographical machine equipped 75 with assembling and distributing mechanisms, the combination of a series of parallel pivoted magazines, means for shifting the magazines rectilinearly to bring a selected plurality into cooperation with the distributing mechanism, means for swinging the magazines about their respective pivots to bring any magazine of the selected plurality into cooperation with the assembling mechanism, and means for automatically shifting the pivots of the magazines of the selected plurality relatively to one another to insure such cooperation.

10. In a typographical machine equipped 80 with assembling and distributing mechanisms, the combination of a plurality of magazines, a supporting frame therefor provided with perpendicular corner members and shiftable to bring a selected plurality of magazines into operative relation 85 to the distributing mechanism, magazine base frames provided with pivot pins engaging notches in said corner members, means for swinging the base frames about their respective pivots to bring any magazine of the selected plurality into operative relation to the assembling mechanism, stationary brackets wherein the corner members are guided, and cam plates secured to the stationary brackets and upon which the 90 said pivot pins track as the supporting frame is shifted, the said cam plates serving to shift the magazine base frames longitudinally, for the purpose described.

11. In a typographical machine, the combination of a plurality of distributors, magazine entrances leading therefrom, a corresponding plurality of magazines arranged in operative relation thereto and pivotally mounted at their upper ends, adjacent the lower ends of the magazine entrances, an assembler entrance, and means for swinging the magazines about their respective pivots to locate one or another in operative relation to the assembler entrance, the said magazine pivots being located in different planes disposed at right angles to the magazines.

12. In a typographical machine equipped 110 with assembling and distributing mechanisms, the combination of a magazine unit comprising a series of parallel magazines, a supporting frame for said magazine unit, means for shifting the supporting frame to locate a selected plurality of magazines in 115 120 125 130

- operative relation to the distributing mechanism, means for moving the magazine unit relatively to the supporting frame to bring any magazine of the selected plurality into operative relation to the assembling mechanism, means for locking the magazine supporting frame in its shifted positions, and a counterbalancing device for the magazine unit.
- 10 13. In a typographical machine equipped with assembling and distributing mechanisms, the combination of a magazine unit comprising a series of parallel pivoted magazines, a supporting frame for said magazine unit, means for shifting the supporting frame to locate a selected plurality of magazines in operative relation to the distributing mechanism, means for swinging the magazine unit relatively to the supporting frame to bring any magazine of

the selected plurality into operative relation to the assembling mechanism, and a counterbalancing device carried by the shiftable supporting frame and connected to the swinging magazine unit.

25

14. In a typographical machine equipped with assembling and distributing mechanisms, the combination of a plurality of magazines, a shiftable supporting frame therefor, magazine base frames pivoted at their upper ends to the supporting frame, manually operable means for swinging the base frames relatively to the supporting frame, and a spring actuated lever pivoted to the supporting frame and constantly connected to the lowermost base frame.

30

35

In testimony whereof, I have affixed my signature hereto.

DAVID S. KENNEDY.
